UNITED STATES PATENT OFFICE.

CHARLES P. KELLY, OF CHICAGO, ILLINOIS, ASSIGNOR TO THE MORGAN & WRIGHT, OF SAME PLACE.

DESIGN FOR A TIRE.

SPECIFICATION forming part of Design No. 27,830, dated November 9, 1897.

Application filed June 25, 1897. Serial No. 642,348. Term of patent 14 years.

To all whom it may concern:

Be it known that I, CHARLES P. KELLY, a citizen of the United States, residing at Chicago, in the county of Cook and State of Illinois, have invented and produced a new and original Design for Elastic Cushion-Tires, of which the following is a specification, reference being had to the accompanying drawings, forming part thereof.

10 In said drawings, Figure 1 is a side elevation of a tire embodying my design. Fig. 2 shows a section taken transversely through the elastic cushion-tire formed in accordance with my design, together with a portion of 15 the length of such tire illustrated in perspective.

The transverse configuration or outline of the elastic cushion-tire shown in said drawings is substantially as follows: The lower or 20 base portion of the tire comprises the bottom face A and the two side portions B B, which latter are on planes arranged to diverge upwardly from the bottom face A.

The upper portion of the elastic tire is substantially in cross-section an arch or proximate semicircle, formed, however, by an irregular line composed of a succession of reverse curves forming segments of circles, as follows, to wit: The tread proper or extreme 25 upper portion of the tire is formed in outline by the segment C, which at opposite sides merges in the reversely-curved segments D D. The segments D D are succeeded by and merge in the segments E E, which latter are

on curves reverse to the curves of the segments D D. The segments E E are succeeded by and merge in the segments F F, which latter are on curves reverse to the curves of the segments E E and arranged to intersect the planes on which the side portions B B are formed.

The essential feature of my design consists of the tire formed in cross-section with a base having upwardly-diverging side portions and an upper arching or substantially semicircular portion composed of a continuous series of segments successively on reverse curves, one of such segments, which is the highest in point of position, being outwardly convexed and arranged at the tread proper, two of such 35 segments, which are the lowest in point of position, being concaved and arranged, respectively, at opposite sides of the tire and adjacent to the base portion thereof, while between said segment at the tread and each 40 segment adjacent to the base are concaved and convex segments relatively reverse to 45 one another and to the said highest and lowest segments.

Having described my invention, what I 50 claim as new, and desire to secure by Letters Patent, is—

The design for an elastic tire, substantially as herein shown and described.

CHARLES P. KELLY.
